UNITED STATES PATENT OFFICE.

ORIN F. PERRY AND ORIN F. PERRY, JR., OF NEW YORK, N. Y.

MOUNTING FOR MACHINE-GUNS AND THE LIKE.

1,273,179.

Specification of Letters Patent. Patented July 23, 1918.

Application filed February 2, 1917. Serial No. 146,087.

To all whom it may concern:

Be it known that we, ORIN F. PERRY and ORIN F. PERRY, Jr., citizens of the United States, residing at New York city, N. Y., have invented certain new and useful Improvements in Mountings for Machine-Guns and the like, of which the following is a clear, full, and exact description.

This invention relates to improvements in means for mounting machine guns, field telescopes, and other similar instruments upon the ordinary motor-cycle or bicycle. One of the objects of the invention is to provide means for making the mounting for the gun stable and secure, at the same time quickly detachable and easily adjustable by the rider whenever desired.

Other objects of the invention are to provide practical, reliable and simple means for so mounting a machine gun or the like. As the invention is preferably adapted for use with a motor-cycle, a still further object is to provide a mounting which will be light and compact and will not interfere with the operation of the motor-cycle by the rider, and which will at the same time provide a rigid base for holding the gun in position for firing.

The present improvement is designed to enable one man to both operate the motor-cycle and also to use the gun when required. It is contemplated that the best results in the use of this gun will be obtained when the motor-cycle is stationary rather than in motion, and while stationary the machine will be supported in upright position either by the legs of the rider or by the usual fixed stand common to such motor-cycles. The mounting of the gun is so arranged that it may be easily operated and adjusted without the rider leaving his seat.

These being among the objects of the present invention, the same consists of certain features of construction and combinations of parts to be hereinafter described and then claimed with reference to the accompanying drawings illustrating the preferred embodiment of the invention, and in which—

Figure 1 is a side elevation showing the improvements applied to a motor-cycle;

Fig. 2 is a section on the line 2—2, Fig. 3, showing the means for adjusting and holding the gun vertically and horizontally;

Fig. 3 is a horizontal section of the same parts, on the line 3—3 Fig. 2;

Fig. 4 is an enlarged elevational view of a lever-operated clamping device for holding the gun bracket in different angular elevations;

Fig. 5 is a section on the line 5—5 Fig. 2, showing the means for fixing the swivel of the gun and hence the gun in different rotated positions;

Fig. 6 is a detail perspective view of one of the struts of the mounting;

Figs. 7 and 8 are, respectively, a plan view and a side elevation of the foot or cross-piece for supporting the mounting upon the back bone or top bar of the cycle frame, said back bone being also shown;

Figs. 9, 10 and 11 are different views of a foot or cross-piece for supporting the mounting on the front bar of the cycle frame; Fig. 9 being a plan, Fig. 10 a rear elevation, and Fig. 11 a section on the line 11—11 Fig. 10.

Referring more particularly to the drawings, 1 indicates the frame of a two-wheel motor-cycle, having a front wheel 2 and a rear wheel 3 and motor 4 mounted within the frame. The frame 1 has the usual steering head 5 at the front part thereof, and seat support 6 for the saddle 7 upon which the rider sits at the rear part thereof. The usual steering handle bars are indicated at 8, and a swinging stand 9 is mounted at the rear of the frame for supporting the machine when at rest in the usual way. Foot rests for the rider are fixed to the frame at the lower part thereof, one at each side, one of said foot rests being shown at 10. The other details of the motor-cycle are of the usual construction and need not be more specifically described.

The supporting frame or mounting is attached to the motor-cycle for supporting a machine gun such as 11, so that said gun may be easily adjusted for aiming and rapidly manipulated for firing by the rider of the machine when in position upon the saddle 7. The gun should be so mounted that the handle stock 12 and trigger 13 are within convenient reach of the hands of the rider.

The preferred construction of the mounting and means for supporting it so as to support a gun or the like on a cycle is as follows. Referring more particularly to Figs. 2 and 3, a horizontal upper member or plate 14 and a lower horizontal member or plate 15 are provided; these being con-

nected together by means of a pair of front struts 16 and a pair of rear struts 17. Said struts are preferably arranged quadrilaterally as shown, and are suitably connected 5 with the corresponding corners or parts of said members 14, 15. The pair of front struts 16 is provided with a pair of downward, preferably tubular extensions 18 (shown more fully in Fig. 1). Each of the 10 struts 16, 17 is provided with a shoulder 19 which abuts against the undersurface of the lower member or plate 15 of the mounting.

The lower ends of the pairs of struts 16, 17 are preferably extended downwardly below 15 the member 15, so as to provide studs 20, 21, respectively. Studs 20 are telescoped into the upper ends of the tubular strut extensions 18, while the lower ends of the extensions 18 and the studs 21 on the struts 17 20 are seated on and secured to the cycle frame in a manner preferably as now to be described.

The back bone or top bar 22 and the front bar 23 of the cycle frame, Fig. 1, are preferably 25 those portions of the cycle frame with which the mounting is connected. To this end, the back bone 22 supports a foot or cross-piece 24, shown more fully in Figs. 7 and 8. Said foot-piece is provided with a 30 clamp 25 located at about its mid-length, and this clamp may be readily removed from or rigidly applied to said back bone. At the ends of the foot-piece 24 are sockets 26 and set screws 27. The foot-piece 24 serves for 35 directly supporting the pair of struts 17. Another foot or cross-piece 28 serves for supporting the downward extensions 18 of the struts 16. This cross-piece is provided at about its mid-length with a clamp 29 and at 40 the ends with clamps 30, the clamp 29 being set at an inclination to the clamps 30, as shown in Figs. 9, 10 and 11. In practice, the clamp 25 of foot-piece 24 is applied to the back bone 22 so that the sockets 26 45 extend vertically, and the clamp 29 of the other foot-piece is applied to the front bar 23 of the frame of the cycle so as to position the sockets or clamps 30 vertically. The mounting may now be applied 50 to said foot-pieces 24, 28, to which end the lower ends of the downward extensions 18 are inserted in and clamped by the clamps 30; while the studs 21 of the struts 17 are inserted in the sockets 26 and fixed therein by 55 set screws 27. It will now be seen that the frame comprising the downward extensions from the lower member 15 will straddle as it were, the frame of the cycle, and that therefore two of the struts 16, 17, will be located 60 at one side of the cycle frame and the other two at the opposite side. When the said parts are arranged and rigidly set in position as described, an auxiliary frame is constituted which is practically rigid with 65 the cycle frame.

It will be seen that the foot-piece 24 applied to the back bone of the cycle frame will prevent moving of the mounting upwardly away from the cycle frame at the rear end of said mounting and that the foot-piece 28 will prevent upward movement of the front part of the mounting away from the cycle frame. It will also be seen that by reason of the described manner of connecting the struts with said foot-pieces 24, 28, 70 the mounting will be prevented from inclining sidewise of the cycle frame, this being due to the fact that any tendency to so incline is precluded by the connection of the lower foot-piece 28 with the upwardly extending front bar 23, this extending at an angle to the back bone 22. In this manner, the strains from the weight of the mounting of the gun or other part supported thereby and from the shock of explosion are distributed along different members of the 75 frame of the cycle.

Referring more particularly to Figs. 2 to 5, we will now describe the means for adjusting and aiming the gun. The two 90 frame members 14, 15, of the mounting are connected by means of a housing 31 which serves to inclose suitable operating mechanism. A sleeve 32 is fixed to and supported by the top member 14 by means of a set 95 screw 33 which passes through a projecting portion of the upper end of said sleeve and is screwed into said top member, said sleeve extending through corresponding openings in said members 14, 15. Positioned in the 100 sleeve 32 is a swiveled stem 34 which extends upwardly, and at its upper end is provided with a clamping fork 35. As shown more fully in Fig. 4, fork 35 receives a downwardly extending fork 36 on a gun 105 bracket 37, said forks being connected together so as to provide a pivotal movement for the gun bracket 37, by means of a screw threaded pivot pin 38 extending horizontally through said forks. The pin 38 constitutes the pivot upon which the gun may 110 be adjusted to different angular elevations. As a means for setting the connected forks and concomitant parts in adjusted position, nuts 39 are screwed on to the pin 38 at one 115 end, while between the head of said pin at the other end and the fork 35, coacting cam surfaces 40, 42 are provided, the cam surface 40 being on the fork 35 and the cam surface 42 being upon a lever 41. Said lever 120 41 is located between the head of the pin 38 and cam surface 40, so that by swinging the lever partially around, after the nuts 39 have been set to desired position, the cam surfaces 40, 42, will bear upon each other so 125 as to shift the pin 38 axially, thereby producing a very firm binding engagement of the involved parts. The gun is also provided with a locking pin 43 to fasten it on the mount. 130

The before mentioned swiveled stem 34 is provided with a series of circular rack teeth 44 which have frictional engagement with the inner wall of the sleeve 32, and said sleeve is provided at its upper end with a slot 45, located diametrically opposite the set screw 33. Rack teeth 44 are arranged so that they may mesh with the teeth of a pinion 46 which is located upon a horizontal 10 shaft 47 mounted in bearings of the housing 31. It will be seen that inasmuch as the rack teeth are circular and are not continuous one with the other, said teeth may be engaged by said pinion at all portions of 15 their peripheries so that by means of said pinion the said stem may be elevated and lowered in any position in which it may happen to be turned. Upon the pinion shaft 47 there is located a worm-wheel 48 20 which is in mesh with a worm 49 of a horizontal shaft 50 extending transversely of the shaft 47 and mounted in suitable bearings of the housing 31. A hand-crank 51 is arranged at one end of the worm-shaft 25 50 for rotating it.

By means of the slot 45 in the sleeve 32, the upper end of said sleeve is split so that the resiliency thereof may be made use of to bind the stem 34 within the split portion 30 of said sleeve or free said stem therefrom. As a means for expanding and contracting the split portion of said sleeve, the upper end thereof is provided at opposite sides of said slot 45 with ears 52, a headed pin 53 35 passing through said ears and a cam lever 54 being pivoted to said pin, as shown in detail in Fig. 5. It will be seen that by operating the cam lever the split sleeve will be expanded or contracted as desired.

40 In the operation of the described mounting for fire arms or the like, the motor-cycle is first brought to rest as above stated, the rider remaining astraddle of the machine and either supporting it in upright 45 position by his legs, or throwing down the frame 9 at the rear to provide a further support. In any position the rider has the gun directly in front of him, and, if necessary, elevates it to proper position by turning the 50 hand-crank 51. Then, if necessary to swing the gun horizontally, the clamp furnished by the split upper end of sleeve 32 is operated and the clamp loosened by means of the lever 54 and the gun is swung around. 55 If a further, angular, adjustment is required, lever 41 is operated to loosen the clamping action, whereupon the gun may be swung up or down to different angular positions. It may be desirable to operate 60 the gun with these clamps all loosened, so that the gun can be rapidly turned from side to side and up and down, but if desired, any one of the adjustments may be set in fixed position for a more steady firing in 65 one direction.

It will be observed that by means of this improvement we have provided a very mobile firing unit which may be rapidly shifted from place to place and which may be easily aimed and fired at all times, either 70 with the motor-cycle stationary or in motion, and with the least amount of attendance and trouble.

This application is in part a continuation of our former application filed August 9th, 1916, Serial No. 113,953. 75

It is obvious that the improvement is susceptible of wide variations in detail, and we desire it to be understood that the scope of the claims is not to be limited to the 80 particular embodiment shown, that being merely the preferred form of the invention for illustrative purposes only.

What we claim as new is:

1. The combination with a two-wheel cycle, having a steering handle and a rider's seat, of a mounting for supporting a machine gun or the like, said mounting comprising substantially parallel supporting struts connected with and rigidly supported 85 by two different members of the frame of said cycle, at points below said mounting but in advance of said seat.

2. The combination with a two-wheel cycle, having a steering handle and a rider's seat, of a mounting for supporting a machine gun or the like, located between the handle bars of said handle and in front of 95 said seat, said mounting being detachably and rigidly connected with two different 100 members of the frame of said cycle, at points below said mounting but in advance of said seat.

3. The combination with a two-wheel cycle, of a mounting for supporting a machine 105 gun or the like, supporting means for said mounting, connected with the top bar of the cycle-frame, and supporting means for said mounting, connected with the front bar of 110 said frame, both of said supporting means being rigidly connected with said members at points below said mounting, and each of them resisting the movement of said mounting in a different direction from the other.

4. The combination with a two-wheel cycle, of a mounting for supporting a machine gun or the like, paired supporting struts for 115 said mounting, connected with one member of the cycle-frame, and paired supporting struts for said mounting, connected with another member of said frame, both of said supporting struts being rigidly connected with said members at points below said mounting, and each pair of them resisting the movement of said mounting in a different 120 direction from the other pair.

5. The combination, with a two-wheel cycle, of a mounting for supporting a machine gun or the like upon the cycle frame, and front and rear supporting means for said 125

mounting, straddling and connected with said frame at two points, one in advance of the other.

6. The combination, with a two-wheel cycle, of a mounting for supporting a machine gun or the like upon the cycle frame, and front and rear supporting means for said mounting, straddling and connected with said frame at two points, one in advance of the other.

10 the other, but below said mounting.

7. The combination, with a two-wheel cycle, of a mounting for supporting a machine gun or the like upon the cycle frame, and front and rear supporting means for said mounting, straddling and connected detachably with said frame at two points, one in advance of the other.

8. The combination, with a two-wheel cycle, of a mounting for supporting a machine gun or the like upon the cycle frame, and a pair of front and a pair of rear supporting struts for said mounting, straddling and connected with said frame at two points, one in advance of the other.

20 9. The combination, with a two-wheel cycle, of a mounting for supporting a machine gun or the like, front and rear supports for said mounting, means for detachably connecting said rear support with the top bar 30 of the cycle frame, and means for detachably connecting said front support with the front bar of said frame.

10. The combination, with a two-wheel cycle, of a mounting for supporting a machine gun or the like, front and rear supports for said mounting, a cross bar provided with clamping means for detachably connecting said rear support with the top bar of the cycle frame, and a cross bar provided with 40 clamping means for detachably connecting said front support with the front bar of said frame.

11. The combination, with a two-wheel cycle, of a mounting for supporting a machine gun or the like, front and rear supports for 45 said mounting, a cross bar provided with clamping means for detachably connecting said rear support with the top bar of the cycle frame, and a cross bar provided with 50 clamping means for detachably connecting said front support with the front bar of said frame, each of said supports consisting of a pair of struts, and the struts of each pair being attached to their corresponding cross 55 bar.

12. The combination with a two-wheel cycle, of a detachable mounting, rigidly supported on the frame of said cycle between the handle bars, for supporting a machine 60 gun or the like, having a supporting frame, comprising a swiveled stem located in said supporting frame on a line vertically intersecting the top bar of said cycle for adjusting said gun both vertically and horizon-

tally, and means for adjusting said gun at 65 different angles of elevation.

13. The combination with a two-wheel cycle, of a mounting for supporting a machine gun or the like, comprising a supporting stem swiveled on a vertical axis and having 70 circular rack teeth thereon, and an operating pinion engaging said rack teeth to elevate and lower said stem.

14. The combination with a two-wheel cycle, of a mounting for supporting a machine gun or the like, comprising a supporting stem swiveled on a vertical axis and having 75 circular rack teeth thereon, an operating pinion engaging said rack teeth for elevating and lowering said stem, and a worm 80 drive comprising a hand crank for operating said pinion to elevate and lower said stem.

15. The combination with a two-wheel cycle, of a mounting for supporting a machine gun or the like, comprising a supporting stem swiveled on a vertical axis and having 85 circular rack teeth thereon, and an operating means for engaging said rack teeth to elevate and lower said stem.

90 16. The combination with a two-wheel cycle, of a mounting for supporting a machine gun or the like, comprising a supporting stem swiveled on a vertical axis and having 95 rack teeth thereon, and an operating means for engaging said rack teeth to elevate and lower said stem.

17. The combination with a two-wheel cycle, of a mounting for supporting a machine gun or the like, comprising a supporting stem swiveled on a vertical axis and having 100 rack teeth thereon, an operating means for engaging said rack teeth for elevating and lowering said stem, and a worm drive comprising a hand crank for operating said 105 operating means to elevate and lower said stem.

18. The combination with a two-wheel cycle, of a mounting above the top bar of the cycle frame for supporting a machine gun or the like, comprising a supporting stem 110 swiveled on an axis extending vertically above said top bar, and a lever-operated clamping device for holding said stem in different swiveled positions, said clamping device being positioned at the upper end of 115 said stem between the handle bars.

19. The combination with a two-wheel cycle, of a mounting for supporting a machine gun or the like, comprising a supporting stem swiveled on a vertical axis, a lever 120 operated clamping device to hold said stem in different positions, said clamping device being located at the upper end of said stem, rack teeth on said swiveled stem, and operating means for engaging said rack teeth.

125 20. The combination with a two-wheeled cycle, of a mounting for supporting a ma-

chine gun or the like, comprising a supporting member fixed rigidly to the frame of said cycle, a supporting stem having a swivel connection with said member, and power means, said stem and power means having parts for operatively connecting them for raising or lowering said swivel and said gun, the connecting parts for said power means, and also said power means, remaining stationary when said swiveled stem is turned on its axis.

21. The combination with a two-wheel cycle, of a mounting for supporting a machine gun or the like, comprising a supporting stem swiveled on a vertical axis, a lever

operated clamping device to hold said stem in different positions, circular rack teeth on said swiveled stem, an operating pinion engaging said rack teeth, and a worm drive comprising a hand crank for operating said pinion, a supporting bracket attached to said gun and pivoted on said stem to swing on a horizontal axis, and a lever operated clamp to hold said bracket in different angular adjustments.

Signed at New York city, N. Y., this 29th day of January, 1917.
